DESIGN FOR A PICTURE FRAME

Sara Colef, Benton Harbor, Mich.

Application March 14, 1942, Serial No. 106,198

Term of patent 3½ years

To all whom it may concern:

Be it known that I, Sara Colef, a citizen of the United States, residing at Benton Harbor, in the county of Berrien and State of Michigan, have invented a new, original, and ornamental Design for a Picture Frame, of which the following is a specification, reference being had to the accompanying drawing, forming part thereof, in which:

Fig. 1 is a front elevation of a picture frame showing my new design.

Fig. 2 is a top plan view of the same, and Fig. 3 is a sectional view thereof, taken on line 3—3 of Fig. 1.

The characteristic feature of my design resides in the surface decoration of the frame portion of the picture frame which has the appearance of quilted fabric.

I claim:

The ornamental design for a picture frame substantially as shown and described.

SARA COLEF.
